Meyers, Cushman & Rea

UNITED STATES PATENT OFFICE.

CHARLES H. MEIGS, OF PHILADELPHIA, PENNSYLVANIA, ASSIGNOR TO MACANDREWS & FORBES COMPANY, OF CAMDEN, NEW JERSEY, A CORPORATION OF NEW JERSEY.

FIRE-EXTINGUISHING APPARATUS.

1,287,388.

Specification of Letters Patent. Patented Dec. 10, 1918.

Application filed February 7, 1918. Serial No. 215,735.

To all whom it may concern:

Be it known that I, CHARLES H. MEIGS, a citizen of the United States, residing at Philadelphia, in the county of Philadelphia and State of Pennsylvania, have invented new and useful Improvements in Fire-Extinguishing Apparatus, of which the following is a specification.

This invention relates to improvements 10 in fire-extinguishing apparatus, and more particularly to apparatus designed for use in connection with extinguishing of fires by manual manipulation of a vessel carrying the component solutions of an extinguishing medium.

The invention is designed for operation under the general principles pointed out in the application of Frank A. Epps, Ser. No. 160,458, in which the component solutions of a fire-extinguishing compound of the foam-extinguishing type, are normally maintained separate and free from pressure in a receptacle which can be manually manipulated, the receptacle structure being so arranged that the contents of the receptacle can be dashed or thrown toward or dumped upon the point of application (the fire), the component parts of the solution more or less commixing while traveling from the receptacle to the point of application, thus bringing about a condition where a foam effect is started prior to the solution components reaching the point of application. Various ways of arranging the receptacle to produce compartment effects are pointed out in the said application and in other applications by myself, the present invention being designed more particularly for the purpose of producing this compartment formation in a simple and efficient manner with comparatively low cost, and at the same time in such form as will permit the structural elements to be readily shipped in compact form.

Another feature of the invention is the provision of a closure for the receptacle which will normally tend to maintain the solution components in serviceable condition, but which is readily and more or less automatically removed from position to 50 permit the dashing or dumping action taking place in an efficient manner.

To these and other ends, the nature of which will be readily understood as the invention is hereinafter disclosed, said invention consists in the improved construction and combination of parts hereinafter fully described, illustrated in the accompanying drawings, and more particularly pointed out in the appended claims.

In the accompanying drawings, in which 60 similar reference characters indicate similar parts in each of the views:

Figure 1 is a vertical sectional view of a preferred embodiment of the present invention.

Fig. 2 is a view partly in section and partly in elevation showing a plurality of outer receptacles nested together for transportation purposes.

Fig. 3 is a similar view showing a plurality of the inner receptacles nested together for similar purpose.

Fig. 4 is a sectional view with parts broken away and on an enlarged scale indicating the general action which takes place 75 when the cover is being removed automatically.

Fire-extinguishing compounds of the foam-extinguishing type are produced by the commixture of an acid solution and a 80 soda solution, one or both of which carries an ingredient which, when the solution components are commixed, operates to produce a condition of foam which can be described as an "aqueous blanket". This foam formation is non-existent while the solution components remain separate, but is brought into existence when the solution components begin commixing or intermingling, the foam structure remaining intact for a short period 90 and then deteriorating. Various forms of apparatus for providing this foam formation have been employed, and these include the general idea of forming compartments in a receptacle of such type as will permit 95 hand manipulation of the receptacle to dash or dump the contents, such structures being disclosed in the applications above referred to.

In the present embodiment of this general 100 type, the compartment formation is provided by employing two receptacles or ves-

sels which differ in diameter but which are preferably axially alined, thus forming an inner compartment within the inner receptacle and an annular outer compartment between the walls of the two receptacles, so that when the contents are dashed or dumped, the solution component of the inner compartment will, during travel of the solutions, more or less intersect the travel of the solution component from the outer compartment, thus bringing about the intermingling or commixing action desired.

As shown in Fig. 1, the outer receptacle may be in the form of a pail or bucket 10, preferably increasing in diameter toward its open end, 11 indicating the inner receptacle—also preferably increasing in diameter toward its open end—these receptacles being generally of circular contour so as to provide a more or less concentric relation therebetween when arranged on the coincident axis referred to. The inner receptacle is preferably of less depth than that of the outer receptacle.

The two receptacles are removably connected together at their bottoms, a preferred arrangement being by a screw-threaded connection, the male member 10^a being carried by the bottom of vessel 10, the female member 11^a by the bottom of vessel 11. As shown, these members are preferably of comparatively large diameter, thus providing a line of securing engagement of considerable length peripherally as well as locating this securing line toward the outer periphery of the bottom of the inner vessel 11, thus insuring greater stability to the assembly in use. The male and female members may be provided in any desired manner, either as an integral structure with the bottoms or as separate elements secured to the receptacle bottoms.

As will be readily understood, this arrangement permits the inner receptacle to be bodily removed from its position within the outer receptacle by a simple unthreading movement, the inner receptacle remaining intact when removed. As a result, should it be desired at any time to change the contents of either receptacle—deterioration in the solution components may occur after an extended period of non-use—it can be had by simply removing the inner receptacle bodily with its contents, the contents of the outer receptacle remaining therein; hence, the several receptacles can be dumped at separate points and thus avoid the creation of a foamy condition such as may result if both receptacles are dumped at the same point.

Another advantage of this particular arrangement lies in the fact that the inner receptacle can be treated—as by coating—to withstand the effects of the acid—this receptacle being adapted to carry the acid solution component of the compound--and

at the same time the interior of the outer receptacle may be similarly treated if desired, the presence of the inwardly projecting member of each bottom not materially affecting the ability to provide this treating operation.

Another feature however, and this is of material advantage in transportation, is the ability to separate the two receptacles in this manner, leaving each of a configuration such as will enable a plurality of similar receptacles to be nested together, as indicated in Figs. 2 and 3, this result being obtained by the more or less flared formation of each receptacle, and the absence of any material obstruction within a receptacle to prevent such nesting operation, thereby enabling shipment of a number of the receptacle structures in compact form. And, as will be understood, the lowermost inner receptacle may be threaded to the uppermost outer receptacle of the nested series of each, thus enabling the two series to be so located as to reduce the amount of space required for packing or other purposes. Since the male and female members are complementally formed to provide universal mating relation, it will be readily understood that a vessel of each nested series can be readily taken therefrom and assembled by a simple threading action, or, if desired, the solution components may be placed within the two receptacles before assembly, the positioning of the inner receptacle serving to locate the contents of the outer receptacle in proper position.

The outer receptacles are preferably provided with a suitable handle 12. The inner receptacle need not be provided with a handle structure, since its bead will enable the desired operation to be had; obviously, however, the inner receptacle may carry a handle or other simple formation for carrying it about when desired.

As shown in Figs. 1 and 4, I preferably provide a cover for the assembled receptacles, this cover being of a more or less special contour, although the latter may be varied. As shown, the cover, indicated generally at 13, is provided with a depressed central portion 13^a, the rising walls of which are preferably inclined outwardly, as at 13^b, these walls leading into a horizontal portion 13^c, which provides the cover seat, while the outer periphery of the cover is formed by a down-turned bead or flange 13^d. As shown, the rising walls 13^b are of less diameter than the open-top of receptacle 10, and the width of portion 13^c is preferably greater than the width of rolled or beaded top 10^b of the receptacle, the cover thus being loosely mounted on the upper edge of the receptacle, the under face of portion 13^c resting or seating on the top of roll portion 10^b, as shown in Fig. 1. Since the cover

is of metal of comparatively heavy gage, the weight of the cover will be sufficient to normally maintain it seated, the loose mounting not being disadvantageous, since shifting of the cover on the top of the receptacle does not tend to expose the interior of the latter. Obviously, shifting will be restricted by the rising walls 13^b and the bead 13^a.

10 When, however, the assembly is manually manipulated for dashing the contents, thus shifting the axes of the receptacles from the vertical to a more or less inclined position, the weight of the cover will cause it 15 to shift under gravitation, thus bringing the lower portion of the rising wall 13^b into action in connection with the adjacent rounded edge of the receptacle, while that portion of the bead 13^a which is at the top 20 of the assembly in this position will contact with the outer rounded surface of the roll portion 10^b of the outer receptacle, thus bringing about a relation of bead 13^a and roll portion 10^b by which bead 13^a will readily ride up over roll portion 10^b, thus freeing 25 the cover from restraint of the bead portion 13^a, whereupon the entire weight of the cover is placed upon the contacting rising wall 13^b, the width of the seat 13^c permitting 30 a partial raising action by wall 13^b before bead 13^a is freed from restraint. And since the general configuration of the rising wall is such as to provide a more or less cam-like 35 action under these conditions, it will be readily understood that the release of the bead will permit the cover to be automatically shunted off from the receptacle by this cam action, leaving both receptacles with their tops entirely open.

40 This general operation is shown more particularly in Fig. 4, and it will be evident that it permits of more efficient operation of the apparatus through the fact that there is no requirement of first manipulating a 45 cover manually in such manner as to release it, thus eliminating one source of delay in placing the apparatus into action—it being obvious that the excitement naturally present at a time when the apparatus must be 50 placed in use would tend to increase the difficulty of disengaging or releasing the cover. By the general cover formation referred to, however, this removal difficulty is entirely obviated, since it is only necessary 55 to grasp the outer receptacle by its handle and bottom—the usual manner of grasping a pail—and swinging the pail as is usual to provide the impetus to the contents, the cover falling or dropping off during this 60 general movement so that the contents are free to be dashed out or dumped by the continuation of this general manipulation.

While I have herein shown and described a preferred embodiment of the invention, it 65 will be readily understood that the same may

require changes or modifications to meet the exigencies of particular or desired use, and I desire to reserve the right to make any and all such changes or modifications as may be found necessary or desirable in so far as 70 the same may fall within the spirit and scope of the invention as expressed in the accompanying claims when broadly construed.

Having thus described my invention, what 75 I claim as new, is:

1. In apparatus for extinguishing fires by an extinguishing compound formed from a plurality of foam-producing solution components adapted to form a charge for the 80 apparatus and normally maintained free from pressure and in non-contacting juxtaposition with adjacent charge components differing from each other as to solution components, and wherein the extinguishing 85 charge is rendered active by bringing the several components of the charge into mixing relation through dashing or dumping the charge to simultaneously move the solution components toward the point of application, a manually manipulable vessel comprising inner and outer receptacles separably secured together to provide independent open-top compartments for the solution components and with one compartment 90 of annular formation and location relative to an adjacent compartment.

2. In apparatus of the class described, a manually-manipulable vessel comprising inner and outer receptacles differing from 100 each other as to internal dimensions, and means for detachably securing said vessels together to provide independent open-top compartments for the solution components with one compartment of annular formation 105 and location relative to an adjacent compartment.

3. In apparatus of the class described, a manually-manipulable vessel comprising inner and outer receptacles differing from 110 each other as to internal dimensions, and means for detachably securing said vessels together through connection of the respective bottoms of the receptacles, said means locating the assembled receptacles to provide independent open-top compartments for the solution components with one compartment of annular formation relative to 115 an adjacent compartment.

4. In apparatus of the class described, a 120 manually-manipulable vessel comprising inner and outer receptacles differing from each other as to internal dimensions, the bottom of one receptacle carrying an element detachably engageable with a complementary 125 element carried by the bottom of the other receptacle, the relative locations of said elements being such as to locate the assembled receptacles to provide independent open-top compartments for the solution components 130

with one compartment of annular formation relative to an adjacent compartment.

5. In apparatus of the class described, a manually-manipulable vessel comprising inner and outer receptacles differing from each other as to internal dimensions, the bottoms of said receptacles having complementary elements for providing a threaded engagement therebetween, the relative locations of said elements being such as to locate the assembled receptacles to provide independent open-top compartments for the solution components with one compartment of annular formation relative to an adjacent compartment.

6. In apparatus for extinguishing fires by an extinguishing compound formed from a plurality of foam-producing solution components adapted to form a charge for the apparatus and normally maintained free from pressure and in non-contacting juxtaposition with adjacent charge components differing from each other as to solution components, and wherein the extinguishing charge is rendered active by bringing the several components of the charge into commixing relation through dashing or dumping the charge to simultaneously move the solution components toward the point of application, a manually-manipulable vessel comprising inner and outer receptacles separably secured together to provide independent open-top compartments for the solution components and with one compartment of annular formation and location relative to an adjacent compartment, each receptacle having a configuration whereby a plurality of similar receptacles may be nested together for transportation.

40 7. In apparatus of the class described, a manually-manipulable vessel comprising inner and outer receptacles differing from each other as to internal dimensions, the bottoms of said receptacles having complementary elements for providing a threaded engagement therebetween, the relative locations of said elements being such as to locate the assembled receptacles to provide independent open-top compartments for the solution components with one compartment of annular formation relative to an adjacent compartment, said receptacles having individual configurations whereby a plurality of similar receptacles may be nested together for transportation or storage purposes, the threaded connection of a receptacle of one nested class with a receptacle of the other class permitting transportation or storage of a plurality of receptacles of both classes in compact form.

8. In apparatus for extinguishing fires by dashing or dumping a fire-extinguishing charge to the point of application, and wherein the charge is formed from solution components normally maintained free from

pressure and in non-contacting juxtaposition to prevent commixture of charge components prior to the dashing or dumping action, a vessel having open-top compartments for receiving and storing the charge and manually manipulable to produce the dashing or dumping action, and a cover for said vessel, said cover having a cross-sectional configuration at its seating portion to normally prevent relative shifting movements of the cover and vessel sufficient to expose the interior of the vessel and to permit automatic displacement of the cover to afford free discharge of the charge components when the vessel is manipulated in the dashing or dumping action.

9. In apparatus for extinguishing fires by dashing or dumping a fire-extinguishing charge to the point of application, a vessel having open-top compartments for receiving and storing the charge and manually manipulable to produce the dashing or dumping action, said vessel having a roll or bead at its top, and a cover for the vessel, said cover having a diameter greater than said vessel and having a depressed portion adapted to loosely project into the interior of the vessel with the rising wall of the depression inclined outwardly toward the normal plane of the cover, said cover having its outer periphery in the form of a bead, said cover being positionable on the vessel with the cover bead and rising wall on opposite sides of the rolled or beaded top of the vessel, said cover and vessel configurations normally preventing relative shifting movements sufficient to expose the interior of the vessel and adapted to permit automatic displacement of the cover to permit free discharge of the charge components when the vessel is manipulated in the dashing or dumping action.

10. In apparatus for extinguishing fires by dashing or dumping a fire-extinguishing charge to the point of application, a vessel having open-top compartments for receiving and storing the charge and manually manipulable to produce the dashing or dumping action, said vessel having a roll or bead at its top, and a cover for the vessel, said cover having a diameter greater than said vessel and having a depressed portion adapted to loosely project into the interior of the vessel with the rising wall of the depression inclined outwardly toward the normal plane of the cover, said cover having its outer periphery in the form of a bead, said cover being positionable on the vessel with the cover bead and rising wall on opposite sides of the rolled or beaded top of the vessel, the distance between the rising wall and head of the cover being greater than the width of the rolled edge top of the vessel to form a cover-supporting seat adapted to permit shifting movements of the cover on the ves-

sel, said rising wall and the cover bead normally preventing relative shifting movements sufficient to expose the interior of the vessel, the relative spacing of said wall and bead permitting shifting movements sufficient to permit the rising wall to raise a cover portion in advance of freeing the cover from the restraint of the cover bead when

the vessel is manipulated to provide the dumping or dashing action.

In testimony whereof I have hereunto set my hand in presence of a subscribing witness.

CHARLES H. MEIGS.
